UNITED STATES PATENT OFFICE.

EDWARD SCHENCK, OF COLUMBUS, OHIO, ASSIGNOR TO THE LECHNER MANUFACTURING COMPANY, OF SAME PLACE.

DRAFT-EQUALIZER.

SPECIFICATION forming part of Letters Patent No. 396,609, dated January 22, 1889.

Application filed October 12, 1886. Serial No. 216,018. (No model.)

To all whom it may concern:

Be it known that I, EDWARD SCHENCK, a citizen of the United States, residing at Columbus, in the county of Franklin and State 5 of Ohio, have invented certain new and useful Improvements in Draft-Equalizers, of which the following is a specification, reference being had therein to the accompanying drawings.

10 Figure 1 is a plan view of my invention. Fig. 2 is an edge view looking in the direction of the arrow 1, Fig. 1. Fig. 3 is a detached enlarged view, in perspective, of one of the elbow-levers. Fig. 4 is an edge view of Fig. 3, 15 looking in the direction of the arrow, Fig. 3, and having a section of the cross-bar added thereto.

10 The object of my invention is to equalize the draft of a horse or other draft-animal 20 upon the thills or shafts of a vehicle without the employment of an ordinary long whiffle-tree pivoted centrally to the cross-bar which connects the rear ends of the thills; and to this end it consists in certain details of construction and arrangement, which will be 25 hereinafter explained.

Like letters indicate like parts in all the figures.

30 A A are the thills, and B the cross-bar, which parts may be of any usual or preferred construction.

35 By preference the rear ends of the thills are provided with members of coupling devices, by which they may be attached to the axle.

C D are elbow-levers or bent levers pivoted at b b to the cross-bar.

40 The outer ends, D D, of these levers are provided with T-pieces to facilitate properly connecting the tugs with the levers, substantially as is customary in this class of whiffle-trees. At the inner end of each lever there is a downwardly-projecting lug or stud, c^x, provided with a hook-shaped spur arranged in a 45 plane parallel to the under surface of the lever and at some distance therefrom, the body of the lever having also a similar hook-shaped spur, c. (See particularly Figs. 3 and 4.)

50 C' is a hub or boss projecting from the lower face of the part C of the bent lever, there be-

ing a hole through the hub and the corresponding part of the lever to receive a bolt, b.

E is a cross-bar provided at either end with a pivot-piece, e e, at right angles to the body of the bar and adapted to engage with the 55 outer faces of the lugs. The length of the bar E is such that by preference, when the parts are in proper position, as indicated in Fig. 1, both levers shall lie at an angle to the cross-bar with their outer ends projecting in 60 front of the pivots b b, so that with traces or tugs of equal length the forward pull upon the pivots shall be about the same for both of them.

From the above description it will be readily understood that any excess of pull or motion at the outer end of one of the levers will be immediately transferred through the bar E to the opposite lever, as is customary in 65 this class of whiffle-trees.

70 By means of the girts d' d' the pull upon the outer ends of the levers is transferred almost directly to their ends C C in close proximity to the bar D, whereby the strength and durability of the levers are greatly increased, 75 without a corresponding addition to their weight. After the pivots e e have been placed in working position to the levers the outer ends of the lugs c c are bent around the pivots, thus forming eyes or pivot-seats.

80 By an examination of Fig. 1, in which one of the spurs c is broken away, it will be readily understood that when one of the levers is moved into position indicated in dotted lines the shoulder c' will engage with the bar E and 85 spring the bar out into the curved form indicated by dotted lines x, whereby the elasticity of the bar is utilized to equalize the pull of the horse.

It will also be understood that by reason of 90 the throats in which the ends of the bar E lie and of the lower ends of the pivot-pieces e e lying below the plane of the parts D D of the lever to which the tugs are attached, and nearly down to the plane of the cross-bar, 95 above which the pivot-bolts b b project, the strain upon these bolts is exerted at a point much nearer to the cross-bar in which they are mounted than would be the case if the throats of the levers were in line with the 100

ends of the parts D D, which parts are necessarily arranged at some distance above the upper surface of the cross-bar to permit the tugs to travel backward and forward above 5 the bar, the hollow hub C' resting upon the cross-bar and supporting the body of the lever at a suitable height.

I am aware that elbow levers and bars or links connecting them have been pivoted at 10 their angles to the cross-bars of shafts, and hence do not claim such construction broadly.

What I claim is—

1. In combination with the shafts and the cross-bars, the levers provided with the downwardly-projecting hollow hubs, and with the 15

throats below the parts C C, and the bar E, provided with the cross-pivots mounted in the throats, substantially as set forth.

2. In combination with the shafts and the cross-bars, the levers provided with the downwardly-projecting hollow hubs C', with the throats below the parts C C, and with the shoulders c' c', and the elastic bar pivoted in the throats, substantially as set forth. 20

In testimony whereof I affix my signature in 25 presence of two witnesses.

EDWARD SCHENCK.
